UNITED STATES PATENT OFFICE.

NELSON M. LANGDON, OF CHARLOTTE, MICHIGAN.

LATCH FOR COVERS OR DOORS.

Application filed July 18, 1924. Serial No. 726,772.

To all whom it may concern:

Be it known that I, NELSON M. LANGDON, a citizen of the United States, residing at Charlotte, in the county of Eaton and State of Michigan, have invented certain new and useful Improvements in Latches for Covers or Doors, of which the following is a specification.

This invention relates to an improved latch for covers or doors, being especially designed for fastening and holding shut the engine hoods of motor vehicles, and seeks, among other objects, to provide a device for securing a hood, when closed, to the hood sill, frame or other fixed part of the adjacent structure of the vehicle, supplanting the usual unsightly, obstructive and cumbersome means prevalently provided for this purpose.

The invention further seeks to provide a device which will eliminate rattling while, at the same time, affording flexibility for movement of the hood as caused by the unevenness of the road, and wherein all of the latch structure, with the exception of the handle, will be enclosed beneath the hood.

A further object of the invention, in this connection, is to provide a latch wherein the latch handle may, when the hood is unlatched, be employed for raising the hood, thus obviating the necessity for any special handle for this purpose.

And the invention seeks, as a still further object, to provide a latch which will be simple in its construction as well as in its operation and which may be produced at moderate cost.

Other and incidental objects will appear hereinafter.

In the accompanying drawings:

Figure 1 is a sectional view showing my improved latch applied to a motor vehicle hood,

Figure 2 is a front elevation, the latch handle being shown in section,

Figure 3 is a vertical sectional view similar to Figure 1, but showing a slightly different embodiment of the invention, and

Figure 4 is a front elevation of the embodiment shown in Figure 3, the latch handle being illustrated in section.

Referring now more particularly to Figures 1 and 2 of the drawings, I employ, in carrying the invention into effect, a hook 10 having a shank 11 and integrally connected at one end to said shank is a coil spring 12. Integrally connected to the op-

posite end of said spring is a stem 13 and associated with said stem is a bracket 14 having a central lug 15 through which the stem is screwed or otherwise rigidly and adjustably attached. I have shown the latch applied to a conventional motor vehicle hood 16 and a hood sill is illustrated at 17. As is customary, the hood sills are arranged to overlie the side bars of the frame of the vehicle chassis and I have accordingly indicated one of said side bars at 18. The bracket 14 is riveted or otherwise rigidly secured to the inner side of the hood 16 and formed in the hood, in alinement with the lug 15 of said bracket, is a vertically extending slot 19 surrounding which is an upstanding reinforcing flange 20. Extending freely through said slot is a handle 21 secured at its inner end to the shank 11 of the hook 10 by a nut 22 and forted on or attached to the handle at its outer end is a knob 23, at the base of which is an annular flange 24 to coact with the flange 20 of the hood for limiting the handle in its inward movement through the slot 19 while the flange 20 will serve to space the knob 23 of the handle away from the hood to prevent scratching or marring of the hood. Formed integral with or otherwise rigidly secured to the hood sill 17 or, in the absence of the hood sill, to the frame bar 18 or other adjacent part of the structure of the vehicle, is a catch 25 to cooperate with the hook 10.

In installing the device, and before the handle 21 is attached, the tension of the spring 12 is adjusted by rotating the stem 13 upwardly through the lug 15 of the bracket 14 until the spring will normally hold the handle snugly up against the top of the slot 19, after which the stem is further rotated upwardly sufficiently to give the spring additional tension to properly hold the hood closed when the hook 10 is engaged with the catch 25. Thus, when the hood is initially closed, the hook 10 will be held above the catch 25 so that by grasping the knob 23 of the handle 21, the handle may be depressed for shifting the hook downwardly to the position shown in dotted lines in Figure 1, into engagement with the catch. As the hook is thus shifted downwardly, the lower beveled end thereof will ride over the beveled upper face of the catch so that as the downward movement of the hook is continued, the hook will be directed into engagement with the catch, when the latch

will serve to firmly yet yieldably hold the hood closed. To release the latch, the handle is depressed slightly to disengage the hook 10 from the catch 23, when the spring 12 will immediately function to retract the handle to the upper end of the slot 19 and hold the handle firmly against the upper end wall of said slot. Accordingly, since the handle will thus be maintained in contact with the hood, the handle may be grasped and lifted upwardly for raising the hood.

In Figures 3 and 4 of the drawings, I have illustrated a slightly different embodiment of the invention wherein the hood is indicated at 26, one of the hood sills at 27, and one of the vehicle frame bars at 28. Formed in the hood sill is an opening 29. A hook 30 similar to the hook 10, is employed. The hook 30 is adapted to be freely received through the opening 29 and is provided at one side edge thereof with a bill 31 to engage a catch 31' formed integral with or otherwise rigidly secured to the hood sill or, in the absence of the hood sill, to the frame bar or other adjacent part of the structure of the vehicle. Connected to the hook shank 32 is a handle 33 identical with the handle 23. The handle 33 extends freely through a slot 34 in the hood, which slot is surrounded by a reinforcing flange 35 and is widened toward its lower end. As shown in Figure 4, the slot is provided with a straight edge on one side and a downwardly inclined edge on the opposite side. Integrally connected at one end to the shank 32 of the hook is a spring 36, to the opposite end of which is integrally connected a stem 37 and rigidly and adjustably associated with said stem is a bracket 38 identical with the bracket 14. Thus, as will be seen, the handle 33 may be depressed to project the hook through the slot 29 of the hood sill 27 when the bill of the hook will, as shown in dotted lines in Figure 4, be engaged with the catch 31'. Consequently, upon release of the handle, the spring 36 will function to securely hold the hood closed. To release the hook, the handle is shifted sidewise in the slot 34 to free the bill 31 of the hook when, upon release of the handle, the spring will retract the handle to the top of the slot 34 in the hood, firmly holding the handle against the upper end wall of said slot so that the handle may be employed for raising the hood.

Having thus described the invention, what I claim is:

1. A latch including a bracket for rigid attachment to an element to be latched, a hook, a spring integrally attached at one end to the hook, a stem integrally attached to the opposite end of the spring and screwed through said bracket rigidly and adjustably mounting the spring, and a handle rigidly

secured to the hook at one side thereof and operable for flexing the spring and manipulating the hook.

2. The combination with an element to be latched, of a bracket fixed to said element, a spring having an integrally attached stem rigidly and adjustably connected with said bracket, a hook carried by the spring, said element being provided with a slot, a handle extending through said slot and rigidly attached to the hook, the handle being operable for flexing the spring and manipulating the hook guided by said slot, and a protecting and reinforcing flange surrounding said slot.

3. The combination with an element to be latched having a slot therethrough, of a bracket rigidly fixed to said element, a hook, a spring integrally attached at one end to said hook, a stem integrally attached to the opposite end of said spring and screwed through said bracket rigidly and adjustably mounting the spring, and a handle extending through said slot and rigidly secured to said hook, the handle being operable for flexing said spring and manipulating the hook guided by said slot.

4. The combination with an element to be latched having a slot therethrough, of a bracket rigidly fixed to said element, a hook, a spring integrally attached at one end to said hook, a stem integrally attached to the opposite end of said spring and rigidly and adjustably engaged with said bracket, a handle extending through said slot and rigidly secured to said hook, the handle being operable for flexing said spring and manipulating the hook guided by said slot, and a reinforcing flange surrounding said slot.

5. The combination with a structure having a fixed part, and an element to be latched to said part and having a slot therethrough, of a bracket rigidly fixed to said element, a hook, a spring integrally attached at one end to said hook, a stem integrally attached to the opposite end of said spring and screwed through said bracket rigidly and adjustably mounting the spring, a handle extending through said slot and rigidly secured to said hook, the handle being operable for flexing said spring and manipulating the hook guided by said slot, and a catch on said fixed part engageable by said hook.

6. A latch including a bracket, an integrally connected hook, spring and stem unit having the stem thereof screwed through said bracket rigidly and adjustably mounting the spring, and a handle carried by the hook and operable for flexing the spring of said unit and manipulating the hook.

7. The combination with an element to be latched having a slot therethrough, of a bracket fixed to said element, an integrally connected hook, spring and stem unit having the stem thereof screwed through said

bracket rigidly and adjustably mounting the spring, and a handle rigidly fixed to the hook to extend through said slot, the handle being operable for flexing the spring of said unit and manipulating the hook guided by said slot.

8. The combination with an element to be latched having a slot therethrough, of a bracket fixed to said element, an integrally connected hook, spring and stem unit having the stem thereof screwed through said bracket rigidly and adjustably mounting the spring, and a handle rigidly fixed to the hook to extend through said slot and normally held by the spring of said unit firmly

against one end wall of the slot, the handle being operable for flexing the spring of said unit and manipulating the hook guided by said slot.

9. In a latch, the combination with a fixed 20 part, a hook, a spring carrying the hook, a handle carried by said hook and operable to stretch said spring and engage the hook with said part, of means rigidly mounting the spring and adjustable to vary the tension 25 on the spring when the hook is engaged with said part.

In testimony whereof I affix my signature.

NELSON M. LANGDON.
